UNITED STATES PATENT OFFICE.

RODERICK G. COLLINS, JR., OF NEW YORK, N. Y.

CONDUIT AND CAR FOR PNEUMATIC RAILWAYS.

1,120,133.

Specification of Letters Patent.

Patented Dec. 8, 1914.

Application filed March 4, 1914. Serial No. 822,507.

To all whom it may concern:

Be it known that I, RODERICK G. COLLINS, Jr., a citizen of the United States, residing at New York, in the county of New York and State of New York, have invented new and useful Improvements in Conduits and Cars for Pneumatic Railways, of which the following is a specification.

The present invention relates to pneumatic despatch apparatus, more particularly to an improved pneumatic tube and carrier therefor, and has for one of its objects to provide a pneumatic tube of such construction that it may be made of cementitious material. In forming the tube of cementitious material a tube or conduit is provided which may be cheaply laid, and wherein wear plates may be embedded in the cementitious material to take care of the wear and tear incident to the passage of the carriers through the tube, the wear plates constituting reinforcing and strengthening means prolonging the life of the tube or conduit.

Another object of this invention is to provide a pneumatic tube and carrier of such cross-sectional shape that the carrier will not turn about its longitudinal axis during its passage through the tube, and wherein in the carrier has a greater cross-sectional area so as to provide for a relatively large space for accommodating the load.

In carrying out this latter object of the invention, provision is made whereby there is practically no turning movement of the carrier within the tube, and wherein the pneumatic tube is trackless, and at the same time admitting of the installing of automatic switches, particularly of the selective type. This is accomplished by providing the carrier with an adjustable tripper, or the like, which as the carrier is maintained in upright position at all times, will remain in the adjusted position relative to the switch operating mechanism so that the operation is positive and accurate at all times.

In order that the invention may be clear to those skilled in the art, I have shown in the accompanying drawings one embodiment of the invention, the same being merely illustrative and not restrictive of the invention, for I reserve the right to make such mechanical changes as may be found necessary to adapt the invention to different circumstances, all of which being within the purview of my invention.

In the drawings,—Figure 1 is a cross section of a conduit in accordance with my invention. Fig. 2 is a longitudinal section of a portion of the conduit shown in Fig. 2. Fig. 3 is a diagrammatic view of the conduit constructed at a curve. Fig. 4 is a cross section of the conduit at the apex of a curve. Fig. 5 is a cross section of the same showing a slightly different construction. Fig. 6 is a cross section of a conduit showing a modified form of the same. Fig. 7 is a longitudinal section of a portion of the bottom of the conduit showing a slightly different form of reinforce. Fig. 8 is a similar view disclosing another form of reinforce.

Referring to these drawings, wherein like numerals indicate similar parts throughout the several figures, 10 designates the pneumatic tube or conduit which may be formed of any suitable cementitious material, and which is laid into a suitable trench or suitable supporting forms. The bore 11 of the conduit or tube is made U-shape in cross section, although any other cross-section may be given the bore provided that the cross-section presents a non-circular bore for a purpose which will hereinafter appear. The body of the tube or conduit 10 is preferably reinforced by longitudinally extending tie-rods 12 arranged in the side walls of the tube. It is of course understood that these tie-rods can be arranged in any suitable manner. For the purpose of protecting and reinforcing this cementitious tube, which is of material more or less friable and tending to disintegrate under constant rubbing of the carrier wheels, I provide wear-plates, preferably of metal, located in the inner walls of the tube at points where the carrier wheels engage the tube. These wear plates are placed at different positions in the tube according to the location of the carrier wheels, and in the construction shown in Fig. 1, I have shown the same as comprising metal tread plates 13 being rounded or arched to conform to the bore 11 and lying substantially flush with the surface thereof so as to provide a smooth uninterrupted bore. These tread plates 13 are anchored in the body of the tube by

depending legs 14 embedded firmly in the cementitious material to prevent any shifting of the plates. It is, of course, understood that these plates may be of any desired length and that they are placed end to end throughout the length of the tube. To insure the anchoring of the legs 14 in the body of the tube, I provide tie-rods 15 which, as shown in Fig. 1, may pass transversely through the legs 14 and beyond the same or, if preferred, the tie-rods may extend longitudinally through the legs 14 as shown at 15^a in Fig. 7. Further, the tie-rods 15 of Fig. 1 may be supplemented by 15 the addition of the longitudinal tie-rods 15^a, as shown in Fig. 8.

The car or carrier, designated by 16, corresponds in cross-section to the shape of the tube. The carrier is provided with end plates 17 each of which is provided with a supporting wheel 18 at its lower end adapted to engage and move over the tread plates 13. On either side of each of the main supporting wheels 18 are preferably arranged buffer wheels 19 to take care, to a certain extent, of the side thrust or rock of the carrier. These buffer wheels 19 also contact with the metal tread plates 13, and if desired the latter may extend up toward 30 the sides of the tube for engagement with the buffer wheels, as shown. The upper end of each plate 17 carries at its opposite sides a pair of horizontal buffer wheels 20 which project slightly beyond the lateral edges 35 of the plate 17 and are adapted to engage the sides of the pneumatic tube when the carrier rocks, for instance as when rounding a horizontal curve, to retain the carrier in upright position and reduce frictional 40 contact between the carrier and the tube. Each end plate 17 is further provided with a vertical buffer wheel 21 at its upper end adapted for engagement with the roof 22 of the tube when the carrier rises in the 45 tube in passing over ridges or where the conduit curves in a vertical plane. From Fig. 1 it will be noted that wear-plates 23 of angular form are embedded in the cementitious material at the angles of the 50 tube, the vertical depending flanges of the wear-plates 23 lying directly opposite to the side buffer wheels 20 at the top of the carrier. The angle wear-plates 23 are anchored in the cementitious body by L-bolts 55 24 arranged in staggered relation in the opposite flanges of the wear-plates 22, and in the sides and roof of the tube. The wear-plates 23 lie flush with the inner surface 60 of the tube and may be retained in position in any other suitable manner than herein disclosed. These wear-plates 23 also serve as reinforcements for the upper portion of the tube, materially strengthening the same at the upper corners.

65 In Fig. 6 of the drawings a modified con-

struction of the tube and carrier is shown. In this construction the tube 10 is of substantially the same shape as shown in Fig. 1 but is provided with a flat roof 22^a instead of an arched roof. The roof 22^a is 70 reinforced, preferably throughout its entire width, by a wear-plate 23^a extending entirely across the roof 22^a and having its opposite sides embedded in the corners of the tube 10. The end plate 17 of the carrier 75 has the horizontal buffer wheels 20^a dropped down to an intermediate point at the lateral edges of the plate 17 instead of at the top thereof, and the tread plate 13^a is extended up within the inner surface of the tube to a point opposite to, or slightly above the buffer wheels 20^a, so as to receive the impact of these buffer wheels and prevent undue wear upon the inner surface of the tube, particularly when the carrier is rounding a 80 curve. Instead of providing one central buffer wheel 21 at the top of the end-plate 17, a pair of upper buffer wheels 21^a are mounted on the plate, one near each corner thereof, and adapted to bear against the wear-plate 23^a upon the rocking or lifting 85 of the carrier in the tube. It will thus be noted that the wear-plates used within this improved tube are to be placed at any point found necessary or desired to receive the 90 impact of the supporting and buffer wheels 95 of the carrier.

In pneumatic tube systems, particularly of the tube herein disclosed, the strain is greatest at the curves in the tubes or conduits due to the fact that the cars or carriers are swung from a right line to a curve. To compensate for this strain, I preferably incline the vertical axis of the bore of the tube, as shown in Figs. 4 and 5 of the drawings, so that the swinging or side thrust of the car in taking a curve will be cared for. The thus tilted bore of the tube has the effect of easing the car around the curves even at a high speed without undue side 100 thrusts on the walls of the tube, the inclining of the vertical axis being dependent on the curve and being proportioned to give the necessary compensation for side thrusts due to the tendency of the car to travel 105 tangentially.

In Fig. 4 of the drawings I disclose the bore 11 of the conduit formed eccentrically in the body 10 of the tube, or in tilted relation to the vertical axis of the tube, the 110 latter being disposed in upright position. In Fig. 5, I show the bore formed concentrically in the body 10 and the entire body 10 of the tube tilted in the trench or supporting form, so that the bore of the tube 115 will have its vertical axis correspondingly tilted. It will be understood that the curved portion of the conduit is tilted gradually from a proper position near the beginning 120 of the curved portion of the apex thereof, 130

and is then gradually righted in like manner to a similar point slightly beyond the end of the curve.

In Figs. 1 and 6 of the drawings I have shown, diagrammatically, an automatic switch throwing mechanism wherein the arm 25 of the mechanism projects out from the surface of the bore 11 a slight distance, and wherein the carrier head or end plate 17 is provided with an adjustable striker or tripper rod 26. It will be noted that the tripper rod 26 must always be maintained in the path of the projecting arm 25 in order to throw the switch. It is readily seen that as the carrier 16 is maintained in the same relative position to the bore at all times the tripper rod 26 is maintained in its true path and the striking of the tripper rod 26 against the projecting arm 25 is insured. It is of course understood that the switch throwing device herein is only diagrammatically shown, and the same may comprise operating levers to mechanically throw the switch, or the device shown may be electric contacts to close circuits to operate the switch electrically.

It will thus be seen that the car is maintained in its upright position to produce the above noted advantages without the use 30 of rails or other auxiliary devices which have been heretofore used to effect this result.

It is necessary in pneumatic tube systems that the carriers fit the tubes relatively close in order to conserve pressure. Where curves of relatively small radius are formed in the tubes considerable difficulty is experienced in handling cars of any considerable length, owing to the fact that if 40 the curve be a sharp one the carrier would jam. To overcome this difficulty and permit the use of relatively long cars I have devised the conduit construction shown diagrammatically in Fig. 3. In this figure the 45 curved portion of the conduit has its opposite walls spread relatively far apart to increase the width of the bore 11. The bore in the curved portion of the tube is increased in diameter gradually from its beginning to its apex and then decreased in like manner to the point where it merges into the straight section of the tube.

Referring to Fig. 3 it will be seen that the dotted line 27 indicates the true curve of 55 the inner wall of the tube, and obviously the car 16 would not pass such a curve without jamming. The inner segment 28 of the tube is, therefore, somewhat flattened so that the bore is increased in width between 60 the outer wall 29 of the curve and the inner wall 28. This construction gives a flared or expanded section in the curve about which the car will readily pass, and this I regard as of considerable importance in this 65 art for the reason that it permits the use

of cars of considerable length in conduits where relatively sharp turns must be taken.

By providing a carrier which is substantially U-shape in cross-section a greater amount of space is provided in the carrier 70 than carriers heretofore known which are of circular cross-section. It will thus be seen that with a carrier of given length, constructed in accordance with my invention, a larger load may be carried than with the 75 old form of carrier.

While I have shown a particular construction it will be understood that the bore of the tube and the carrier may be given any other shape which is non-circular so as to 80 prevent the turning of the carrier in a tube without the use of tracks or other like devices, and the various details of construction above enumerated, and disclosed in the drawings, may be changed to accommodate 85 my apparatus to various conditions without departing from the spirit of my invention except insofar as I am limited by the appended claims. It is also understood that the tube above described may be made 90 of other material than cementitious material, such as metal, without departing from the spirit of my invention.

I claim—

1. In a pneumatic despatch apparatus, a 95 tube comprising a body of cementitious material having a non-circular bore, a carrier in said tube conforming to the shape of said bore, supporting wheels at the lower end of the carrier, buffer wheels at the sides of the 100 carrier adapted to support the carrier when rounding a curve, a tread-plate in the bottom of the tube flush with the surface of said bore and having depending legs embedded in the cementitious material, tie-rods extending through said legs and the cementitious material for anchoring said tread-plate therein, wear-plates embedded in the tube at the upper end thereof opposite said buffer wheels, and means for anchoring said wear-plates in the tube. 105

2. In pneumatic despatch apparatus, a 110 tube of cementitious material having a substantially rounded bottom and a non-circular top in cross-section, a wheeled carrier 115 for said tube conforming to the shape thereof whereby said carrier is maintained in an upright position, and a curved wear plate in the bottom of the tube substantially flush with the surface thereof and adapted 120 to support the wheels of the carrier and upon which the wheels are free to move laterally.

3. In pneumatic despatch apparatus, a 125 tube of cementitious material having a bore rounded at its bottom and non-circular at its top, a tread plate in the bottom of the tube having its face substantially flush with the surface thereof and adapted to support a carrier, and wear plates in the top 130

of the tube adapted to receive the thrust of a carrier when rounding a curve and lying substantially flush with the top wall of said bore and constituting a continuation of the 5 surface thereof.

4. A pneumatic despatch tube of cementitious material having a bore rounded at the bottom and non-circular at the top, said tube at curves having its vertical axis 10 placed outwardly at the lower portion whereby substantially all of the thrust of a carrier in rounding curves is received by said rounded bottom.

5. A pneumatic despatch apparatus, a 15 tube of cementitious material having a rounded bottom and a non-circular top in cross-section, a carrier for said tube having a substantially rounded bottom and a non-circular top, a main carrying wheel on each 20 head of the carrier, said carrying wheels having their rims projecting slightly beyond the peripheries of the heads for contact with said rounded bottom to support the carrier, and buffer wheels mounted on 25 the said heads at the opposite sides of said carrying wheels and projecting slightly beyond the peripheries of the head for contact with the tube to reduce frictional contact between the carrier and the tube.

30 6. A pneumatic despatch tube of cementitious material having a bore non-circular at its top and rounded at its bottom and adapted to receive a carrier, a tread plate in the bottom of the bore having a curved 35 carrier supporting face substantially flush

with the surface of the bore and having anchoring members embedded in the cementitious body for securing said tread plate in the tube.

7. In pneumatic despatch apparatus, a 40 despatch tube of cementitious material having a bore with a rounded bottom and an angular top, a tread plate on the bottom of the tube having a curved carrier supporting surface, means for anchoring the tread plate in the tube, angular wear-plates 45 embedded in the tube at the corners of said bore adapted to receive the thrust of a carrier thereagainst when rounding curves and to reinforce the tube at its top and means 50 embedded in said material for securing said angular wear plates in position.

8. A pneumatic despatch tube carrier having a rounded bottom and a non-circular top, a carrier wheel mounted on each 55 head of the carrier, said carrying wheels having their rims projecting slightly beyond the peripheries of the heads for supporting the carrier, and buffer wheels mounted on said heads with their axes of 60 rotation at substantially right angles to the adjacent edges of the heads.

In testimony whereof I have hereunto set my hand in presence of two subscribing witnesses.

RODERICK G. COLLINS, JR.
